Primary Examiner — Rosemary K Tarcza

(57) **CLAIM**

I, Mathew Inskeep, claim the ornamental design for an integrated battery inverter, as shown in the attached drawings.

DESCRIPTION

FIG. 1 is a top perspective view of the integrated battery inverter showing my new design.

FIG. 2 is a bottom perspective view.

FIG. 3 is a top view.

FIG. 4 is a bottom view thereof.

FIG. 5 is a back view thereof.

FIG. 6 is a front view thereof.

FIG. 7 is a right side view thereof.

FIG. 8 is a left side view thereof.

FIG. 9 is a top front perspective view with the outlet covers opened.

FIG. 10 is a back perspective view with the outlet covers opened.

FIG. 11 is a top view with the outlet covers opened; and,

FIG. 12 is a front view with the outlet covers opened.
